UNITED STATES PATENT OFFICE.

FRANK R. HAHN, OF DECATUR, ILLINOIS.

MOLD.

Application filed February 7, 1919. Serial No. 275,565.

To all whom it may concern:

Be it known that I, FRANK R. HAHN, a citizen of the United States, residing at Decatur, in the county of Macon and State of Illinois, have invented certain new and useful Improvements in Molds, of which the following is a specification.

This invention relates to improvements in molds for molding or casting units made of cement, concrete or other plastic material.

The principal object of this invention is the provision of such a mold construction whereby a plurality of units may be molded or cast at the same time and whereby various kinds of units, this variation referring to size, shape, decoration and the like, may be formed or cast in the same mold.

Further objects of this invention include improvements in details of construction and arrangement, whereby a simple and effective mold is provided which may be readily set up and taken down and operated with facility in the production of a plurality of units or articles.

To the accomplishment of the foregoing and such other objects as may hereinafter appear, my invention consists in the construction, combination and arrangement of parts hereinafter described and then sought to be defined in the appended claims, reference being had to the accompanying drawings forming a part hereof and which show, merely for the purpose of illustrative disclosure, a preferred embodiment of my invention, it being expressly understood, however, that various changes may be made in practice within the scope of the claims without digressing from my inventive idea.

In the drawing—

Fig. 1 represents a top plan view of a mold constructed according to my invention and set up, ready for use.

Fig. 2 is a vertical longitudinal cross section taken substantially on line 2—2 of Fig. 1.

Fig. 3 is a vertical transverse cross section taken substantially on line 3—3 of Fig. 1.

Fig. 4 is a perspective view illustrating the various parts and the manner and method of assembling the same.

Figure 5 is a perspective view of one form of article or unit which may be made in this mold, it being merely for illustrative purposes only.

Figure 6 is a perspective view of a slightly

modified form of the transverse brace member.

Broadly described, this invention comprises a base to which are preferably secured one side and one end piece. This base member is provided with flanges to support a plurality of floor boards or pallets and between which partitions or dividing members may be placed. It is to be understood that suitable decorative impression plates may be placed against the side or end of the mold or on the pallet or on the partition or dividing member, according to the decorative effect desired. The mold further includes the removable side member and end member with means for securing and locking the various parts together.

Referring to the drawing more in detail, the numeral 1 designates the base member of the mold. This is preferably rectangular in shape, though it is obvious that its shape may be varied according to particular working conditions. While this base member may be formed of any material, it is preferred to form the same of steel or similar thin or sheet metal, in the form of a channel, having the sides 2 and the inturned flanges 3 and 4, 3 designating the lower flange, and 4 the upper flange. The upper flanges particularly are of sufficient width to support the pallets, as hereinafter described. The members forming this base are suitably connected by means of the bolts or rods 5, which extend transversely thereacross and the bracing and spreading members 6 may also be utilized to assist in holding the parts of the base in proper relation to each other. This bracing member 6 is preferably in the form of a channel, having the upper and lower flanges 7 cut away at the end and remaining end extension 8 bent at right angles so as to fit against the inside surface of the side 2 of the channel member forming part of the base. The bolts 5 cooperate with these bracing and spreading members so as to securely brace and hold the base in proper size and shape, which is essential in molding or casting the various articles or units for building construction.

One side 9 and one end 10 are permanently secured in position on said base member 1. While this is preferable it is obvious that this side and this end may be made detachable. It is to be noted that I provide slots or recesses 11 at various intervals along the upper corner or edge of one side member and one

end member of the base, these slots or recesses extending partly into the sides 2 of the channel member and partly into the top flange 4 of this channel member. The detachable 5 side member 12 and detachable end member 13 are provided with depending lugs or extensions 14 and 15, 14 designating the lugs or extensions on the side member 12, and 15 designating the lugs or extensions on the 10 end member 13. These lugs or extensions on the side and end members are adapted to slip thru said slots or recesses 11 in the side and end members of the base 1. Due to the size of these slots or recesses 11, the side 15 and end members may be inserted at an angle and then moved upwardly until the depending lugs or extensions 14 and 15 bear against the vertical sides of the channel member of the base 1, whereby the side and 20 end members are positively held in true vertical positions relative to said base member.

It is to be understood that prior to the mounting of the removable side member 12 and removable end member 13 that suitable 25 floor boards or pallets 16 are placed in the mold, resting upon the inturned upper flanges 4 of the base and that these pallets are separated by suitable partitions or dividing members 17, which may be decorated 30 or not, depending upon the character of work being made.

When the side member 12 is placed in position it is secured at one end to the stationary end member 10 by means of a hook 35 or similar securing means 18. The end member 13 is then placed in position and moved to its proper vertical position and the locking bail 19 is forced into position. This bail has the elongated part 20 for engaging 40 the end member 13, and the side parts 21 for engaging the side members 9 and 12 and to rest in the clips or brackets 22, which side parts 21 have the laterally turned end portion 23 to prevent relative 45 longitudinal movement between the bail and the clip or bracket 22. It is to be noted that the upper outer edge of the end member 13 is beveled or rounded, as at 24, so as to permit said bail to be readily forced into 50 locking position. It is also to be noted that the inside lower edge of the end member 13 is rounded or beveled, as at 25, so as to permit this member to be moved upwardly and have a sort of wedging or pressing action 55 against the adjacent floor board or pallet and consequently all of the other members to force and hold them in proper position.

In addition to the locking means previously described, it may be found advisable 60 to provide additional means for forcing the sides into proper position. One form of such a means is illustrated in the drawing. It includes making the end member 13 in two parts 26 and 27. The lug members 15 65 are secured to the part 26. Pins 28 pass

thru said member 26 and are secured to member 27 and also pass thru the lug members 15 to form a guide for said members 27, having springs 29 on the outside thereof to resist separation of the two members 26 and 27. The manually operated cam members 30 are pivoted to said lug members 15 and pass thru a suitable slot in member 26 into engagement with member 27. It is obvious that when these cam members are moved to the position shown particularly in Fig. 2, that the member 27 will be forced inwardly against the tension of springs 29, so as to force the floor boards or pallets 16 and partitions or dividing members 17 closely in association with each other so that the units or parts molded or cast therein will all be of proper size.

It is to be understood that after the mold is set up, as described, the various sections thereof will be filled with cement, concrete or other plastic material used and the top thereof struck off. Depending upon the form of material used, and allowing a sufficient time for the same to set, the mold may 90 be taken down and the various articles removed for drying on their separate and individual pallets. Due to the construction utilized the molds may be piled one upon the other without injury or damage to the contents thereof.

It is therefore to be seen that I have provided a very simple and effective mold for the purpose of casting or molding multiple articles or units at the same time, and which 100 molds may be readily adapted by the use of different kinds of pallets or floor boards and different kinds of dividing members or partitions together with various decorative members to form various kinds of units, 105 decorated or undecorated, as desired. It is also to be noted particularly in the use of a square or rectangular base that the various parts of this mold are self squaring when set up, so that the units or articles will all 110 be molded or cast properly without further attention on the part of the operator.

It is to be noted that in Fig. 6 I show a slight modification in the construction of the brace member 6. In this figure of the drawing it will be seen that the upper flange 7 of this brace member 6 is cut out at a plurality of places, as at 31, the cut out flaps 32 being bent downwardly and then laterally, as at 33, and secured to the inside of 120 the lower horizontal flange of the member 6. This structure is utilized in case it is desirable to mold or cast articles of less width than the width of the mold as a whole. In that case, the side members 12 125 having the proper depending lugs 14 are moved inwardly into the mold and positioned in the proper cut out recess or opening 31, and when straightened up, they will assume a proper vertical position, due to the 130

fact that the lugs 14 will bear against the vertical cut out parts or flaps 32.

Having described my invention, what I claim is:—

- 5 1. A mold, including, in combination, a base member having a plurality of transversely extending brace members, said brace members being provided with a plurality of openings, side and end members for said 10 frame, certain of said side and end members being removable and having means adapted to cooperate with said slots in said brace members so as to vary the effective width of the mold.
- 15 2. A mold including in combination a base member, said base member being rectangular in shape and channel in cross section, having the upper and lower flanges of the channel extending inwardly, said base member having a plurality of slots provided 20 along the upper edge of one side and one end member, one side and one end member being secured to one side and one end of said base member, a removable side and end 25 member having a plurality of depending lugs adapted to fit in said slots, and means for holding said side and end members in assembled relation.
3. A mold including in combination a 30 base member, said base member being rectangular in shape and channel in cross section, having the upper and lower flanges of the channel extending inwardly, said base member having a plurality of slots provided 35 along the upper edge of one side and one end member, one side and one end member being secured to one side and one end of said base member, a removable side and end member having a plurality of depending 40 lugs adapted to fit in said slots, and means for holding said side and end members in assembled relation, a plurality of pallets adapted to rest on the upper flanges of said base member and a plurality of partitions 45 positioned between adjacent pallets, said partitions also resting on the upper flanges of said base member.
4. A mold including in combination a base member in the form of a rectangular 50 frame, transverse bracing and spreading members extending between the sides of said base member and securing means extending between the side members of said base member for frictionally holding said bracing and 55 spreading members in position, side and end members connected to the sides and ends of said frame, certain of said side and end members being removably mounted thereon and means for clamping said side and end 60 members in position.
5. A mold including in combination a base member, rectangular in shape and channel shaped in cross section having its upper and lower flanges extending inwardly, said base member also having a plurality of slots pro- 65 vided along the upper edges of certain of its sides and end members, side and end members adapted to be connected to the sides and ends of said base member, certain of said side and end members having depending lugs 70 adapted to enter said slots whereby they may be removably mounted on said base member, a plurality of pallets adapted to be positioned on the upper flanges of said base member, a plurality of partitions adapt- 75 ed to be interposed between adjacent pallets and resting on the upper flanges of said base member and means for holding said removable side and end members in position.
6. A mold including in combination a 80 base member, rectangular in shape and channel shaped in cross section having its upper and lower flanges extending inwardly, said base member also having a plurality of slots provided along the upper edges of certain of 85 its sides and end members, side and end members adapted to be connected to the sides and ends of said base member, certain of said side and end members having depend- 90 ing lugs adapted to enter said slots whereby they may be removably mounted on said base member, a plurality of pallets adapted to be positioned on the upper flanges of said base member, a plurality of partitions adapt- 95 ed to be interposed between adjacent pallets and resting on the upper flanges of said base member and means for holding said removable side and end members in position, said means including a bail embracing said end member and having a de- 100 tachable connection with the side members of the molds.
7. A mold including in combination a base member, rectangular in shape and channel shaped in cross section having its upper and 105 lower flanges extending inwardly, said base member also having a plurality of slots pro- 110 vided along the upper edges of certain of its sides and end members, side and end members adapted to be connected to the sides and ends of said base member, certain of said side and end members having depending lugs adapted to enter said slots whereby they may be removably mounted on said base member, a plurality of pallets adapt- 115 ed to be positioned on the upper flanges of said base member, a plurality of partitions adapt- 120 ed to be interposed between adjacent pallets and resting on the upper flanges of said base member and means for holding said removable side and end members in position, and means for forcing said pallet and partition into close association with each other.
8. A mold including in combination a base 125 member, rectangular in shape and channel shaped in cross section having its upper and lower flanges extending inwardly, said base member also having a plurality of slots pro- 130 vided along the upper edges of certain of its

sides and end members, side and end members adapted to be connected to the sides and ends of said base member, certain of said side and end members having depending lugs adapted to enter said slots whereby they may be removably mounted on said base member, a plurality of pallets adapted to be positioned on the upper flanges of said base member, a plurality of partitions adapted to be interposed between adjacent pallets and resting on the upper flanges of said base member, means for holding said removable side and end members in position, means for forcing said pallet and partition into close association with each other, said means including an additional element on said removable end member and means con-

nected to said removable end member for forcing said additional element inwardly.

9. A mold including in combination a base member having upper flanges and provided with slots extending through said flanges, side and end members for said frame members, certain of said side and end members having means adapted to co-operate with said slots whereby they may be removably held in position, transversely extending brace members for said frame having a plurality of slots adapted to hold the removable side members in adjusted position to vary the effective width of the mold.

In testimony whereof I hereunto subscribed my name.

FRANK R. HAHN.
